UNITED STATES PATENT OFFICE.

CHARLES C. BISHOP, OF ST. LOUIS, MISSOURI.

ADVERTISING DEVICE.

No. 930,342.

Specification of Letters Patent.

Patented Aug. 10, 1909.

Application filed October 24, 1907. Serial No. 398,929.

To all whom it may concern:

Be it known that I, CHARLES C. BISHOP, a citizen of the United States, and a resident of the city of St. Louis and State of Missouri, have invented a new and useful Improvement in Advertising Devices, of which the following is a specification.

This invention relates to advertising devices. It has for its principal object to produce an attractive and impressive device.

It consists principally in combining with a sign a unique figure or representation of an animate being elaborately, comically or otherwise attired and arranged in any desirable posture, and a talking or sound-producing machine adapted to simulate the voice of such a being.

The invention further consists in the parts and in the arrangements and combinations of parts hereinafter described and claimed.

In the accompanying drawings, which form part of this specification, and wherein like symbols refer to like parts wherever they occur, Figure 1 is a perspective view showing the device arranged in connection with a show window; Fig. 2 is a front elevation of a slightly modified arrangement of the device, with portions broken away to show some of the interior mechanism.

The device as illustrated in the drawings comprises a sign 1 and the figure of a man 2 modishly clothed. The body portion of the figure 2 is preferably made hollow or of skeleton form and has contained therein the mechanism of an ordinary talking or sound-producing machine.

For convenience, the machine is preferably of the cylinder type. Its mechanism comprises a power shaft 3 which is connected with a suitable motor 4. The power shaft 3 is also geared to the usual actuating screw 5 by spur gears 6 and 7 or other suitable connection. Obviously, the operating mechanism is provided with a "switchback" or automatic reversing device of any well known construction for the transmitter or sound-box 8, so that the machine may be made to operate continuously when desirable. Preferably, the transmitter has a sound-amplifying horn 9 connected thereto, whereby the sounds from the machine may be made audible when the device is used in a room or out of doors.

The power shaft 3 of the talking machine mechanism is preferably extended into the casing or frame 1 of the sign device and has a

sprocket wheel 10 fixed on the end thereof. This sprocket wheel is arranged to engage an endless chain 11 so as to actuate the same. The sprocket chain 11 passes around sprocket 60 wheels 12 and 13 on the respective shafts of the rollers 14 and 15. An endless apron 16 is carried by the rollers 14 and 15, and upon this apron advertising signs, pictures and other matter may be placed. The frame or 65 casing 1 is provided with a transparent panel or sight-opening 17 through which the signs may be displayed. By this arrangement, the endless sign-bearing apron is actuated simultaneously with the mechanism of the 70 talking machine. While I have shown an endless apron sign-displaying device, it is obvious that other forms of devices may be employed in lieu thereof.

When the device is placed within a show 75 window or a closed protecting case, means must be provided to carry the sound to the outside. To accomplish this, I prefer to provide a sound-transmitting device comprising a receiving-bell 18 which is preferably elongated at its flaring end so as to always cover the open end of the amplifying horn 9 which is usually arranged to travel with the sound-box lengthwise of the record cylinder. This receiving-bell 18 is connected to a vibratory 80 transmitter 19 which may be of the usual construction provided for telephones. From this transmitter 19 wires 20 lead to a receiver or number of receivers 21 located outside of the show window, as shown in Fig. 1. In 90 this case the receivers 21 are illustrated as being mounted upon a guard rail 22 extending across the front of the window. This rail may be a hollow tube so as to receive the wires 20. The receivers are provided with 95 ear pieces 23 having the properties of ordinary telephone receivers.

In Fig. 1, the figure of the man is shown in a sitting posture and supported by a chair 24. In one hand is held an ordinary telephone 100 transmitter 25 which may be a "dummy"; that is, disconnected. Obviously, the receivers may be constructed and arranged in various other ways than shown, and the parts of the entire device may be arranged in numerous relative positions.

By combining a movable sign with a figure of a human being, and producing the natural voice or sounds of the same, a very attractive, novel and impressive advertising device 110 is produced. The sounds or voice from the machine may refer to the matter on the re-

spective signs, and also may be interspersed with entertaining matter.

Obviously, the device may be modified and arranged in various ways without departing from my invention as defined in the appended claims, and, therefore, I do not wish to be limited to the exact construction shown and described.

What I claim as my invention and desire 10 to secure by Letters Patent is:

1. An advertising device comprising a display device, a figure of an animate being associated therewith, a mechanical device for simulating the natural voice of such a being, 15 a sound-amplifying device in coöperative relation to said mechanical voice-simulating device, and a telephone system arranged in coöperative relation to said sound-amplify-

ing device and adapted to carry the sounds to a point remote therefrom.

2. An advertising device comprising a display device, a figure of an animate being associated therewith, a mechanical device for simulating the natural voice of such a being, and a telephone system adapted to carry the 20 sounds from said mechanical device to a point remote therefrom.

In testimony whereof I have signed my name to this specification in the presence of two subscribing witnesses this 19th day of 25 October, 1907, at St. Louis, Mo.

CHARLES C. BISHOP.
